UNITED STATES PATENT OFFICE.

CHARLES H. LANE, OF CLEVELAND, OHIO.

AIR-SEPARATOR.

SPECIFICATION forming part of Letters Patent No. 728,474, dated May 19, 1903.

Application filed October 25, 1900. Serial No. 34,244. (No model.)

To all whom it may concern:

Be it known that I, CHARLES H. LANE, a citizen of the United States, residing at Cleveland, in the county of Cuyahoga and State of Ohio, have invented a certain new and useful Improvement in Air-Separators, (Case B,) of which the following is a full, clear, and exact description, reference being had to the accompanying drawings.

10 The invention relates to improvements in the kind of apparatus which are so contrived that an air-current may carry off the lighter particles of a pulverized mass and segregate them from the heavier particles which may be recovered at a different point. It is especially applicable to the separation of pulverized ores.

15 The primary object of the invention is to rapidly effect the concentration of the material by carrying away from a large quantity of the material the very light (dust) constituents thereof.

To that end the principal features of the invention reside in the means shown whereby 20 large quantities of air coming from different directions enter the separator chamber or tube, and the pulverized material is delivered in regulated quantities into one air-current before it enters said tube, which current acts 25 to measurably break up the lumps and separate the particles which may have stuck together, so that when they enter the segregating-chamber they will be more quickly acted upon by the segregating air-current therein.

30 The invention consists additionally in the details of construction and combination of parts, as hereinafter described, and pointed out definitely in the claims.

In the drawings, Figure 1 is a side elevation, partly broken away to partially disclose the interior mechanism of an apparatus embodying my invention. Fig. 2 is an end view from the left side of Fig. 1. Fig. 3 is a vertical sectional view on line 3-3 of Fig. 1, and 40 Fig. 4 is an end view from the right side of Fig. 1.

45 Referring to the parts by letters, A represents an inclined cylindrical tube which is closed at its upper end and open at its lower end to a greater or less extent to permit the entrance of air. This tube is supported by a suitable framework B. The outlet for the

air-current is through a large opening c in the top of this tube about midway between its ends, which opening is covered by a large 55 box-like structure C, which forms a passage for guiding and directing the dust-laden air-current. The upper end b of this structure is contracted and adapted for the attachment thereto of a pipe, which may be connected at 60 its other end with a suction-fan or other analogous device by means of which a current of air may be caused to enter the tube A and pass out through the structure C and thence onto the suction-fan. The pulverized material to be acted upon is delivered into the side of the said tube A by the following mechanism, to wit: It is placed in a hopper D, having a contracted discharge-neck d, which is as long substantially as the outlet-opening c of the tube 70 A. One inclined wall d' of this hopper is or may be stationary, while the other is formed by a plate d'', hinged at its upper end, which plate may be moved upon its hinge to vary the relative position of its lower end with the lower end 75 of the side d', thereby varying the size of the outlet-neck of the hopper. The screw-thread arm d'', the rest d'', and the fixed ear d'', through which said arm passes, are the specific devices shown for effecting this adjustment. Just below this neck, but in such a position as to approximately close it, is a rotating feed-roller E. As this roller rotates it carries along with it 80 small quantities of the pulverized material, the quantity depending on the size of the discharge-neck of the hopper, and drops this material into a spout G. The lower end of this spout is in communication with the tube A on one side thereof. This spout, however, has an opening, as at g, through which air 90 may enter and through which it does enter when air is being drawn out of the tube A. The material falling from this feed-roller therefore falls into this current of air by which the particles are separated from one 95 another. When, therefore, these separated particles enter the tube A, they are in condition to be immediately acted upon by the segregating air-current flowing through said tube. The light particles will be caught up 100 by the air-current and carried out through the top of the tube and through the structure C, following the course before pointed out.

The heavier particles will fall to the bottom

of the tube A. With them will fall some of the lighter particles which ought to be carried away and which will be brought under the influence of their current again through 5 the operation of the mechanism which I will now describe.

The tube A, or rather the lower part thereof, is divided into pockets α^3 by the narrow flanges H, which are secured to its bottom 10 and extend part way up its curved sides. These flanges prevent the material which settles onto the bottom of the tube A from flowing by gravity down to its recovery end—that is to say, its lower end. A shaft J extends axially through the tube A and is mounted in suitable bearings in its ends. To this shaft are secured a plurality of substantially radial arms arranged in sets, one for each of the pockets formed by the flanges H. 15 Each set of the arms may consist of one arm or a plurality of arms. The arms are preferably of skeleton form, and a screen β^2 is stretched across the outer end of each. The upper end of the shaft J projects out from 20 the tube A, and it is connected with a driven shaft M by means of a universal-joint connection m^1 , whereby it may be rotated. As it is rotated the arms attached to shaft J pick up the material which has fallen to the 25 bottom of the tube A into the pockets α^3 and lift said material and throw it outward or drop it or sift it through the screen, whereby it repeatedly is subjected to the influence of the current of air in said tube. The light 30 particles, or many of them, will be carried away by this current, while the heavier particles will fall for most part into the pocket α^3 below that from which they were lifted. Owing to the position of the air-outlet opening c in the top or roof of the tube and 35 about midway of its length, the lower end of the tube only is subjected to the strong air-currents, while its upper closed end constitutes a quieter settling-chamber in which there may be mild eddies of air, but no direct 40 sweeping blasts. The mass of material in the lower end of the tube is being constantly carried up by the beaters and dropped through the air-current, which acts with more or less 45 force upon the lighter particles and dust in the falling material, separating them from the heavier particles, whose gravitation it does not overcome. The mastery of the blast over these lighter particles carries them up 50 the inclined tube toward the opening c, where a further separation or sorting of the lighter products takes place, the dust and other lighter matters held in suspension by the air-blast being carried by it out of the opening, 55 while the heavier portions, whose gravity may not be entirely overcome, are given an impetus by the blast that projects them beyond said opening and into the settling-chamber, where they fall to the bottom of the tube 60 to be again picked up by the beaters and work their way down toward the lower end of the tube. By these means I am enabled to sepa-

rate from the mass of material fed into the tube all of the dust and lighter particles that may be influenced and carried upward by the 70 blast in direct opposition to the attraction of gravitation, the remaining lighter portions of the mass being worked over and over again until all of the objectionable matter is removed. This operation is continued until the 75 heavy particles (from which all of these particles which the air can carry away have been removed) reach the recovery-spout K near the lower end of the tube A, through which they fall by gravity. 80

The feed-roller E is constantly rotated from the shaft M by means of sprocket-wheels m and e' , secured, respectively, to it and to the shaft e of said roller, and a sprocket-chain m^2 , which engages with said sprocket-wheels. 85

Having described my invention, I claim—

1. In an air-separator, the combination of an inclined tube closed at its upper end and having an air-inlet opening at its lower end, a feeding-hopper communicating with the interior of the tube and located centrally with respect to the length of said cylinder, an air-exit opening in the upper side of the tube located at a suitable distance away from its closed upper end and beaters revolving in the 90 tube, substantially as and for the purpose set forth.

2. In an air-separator, the combination of an inclined tube having a closed upper end and an air-inlet opening at its lower end, a series of semi-annular flanges within the bottom of the tube, a rotatable shaft mounted axially in said tube and provided with beater-arms whose extremities sweep the spaces between said flanges and an air-exit opening in 105 the upper side of the tube located near its mid-length, substantially as set forth.

3. In an air-separator, the combination of an inclined cylinder closed at its upper end and having an air-inlet opening at its lower end, a feed-hopper communicating with the cylinder midway of its length, an air-exit opening in the upper side of the cylinder also associated midway of the length of said cylinder, and beaters for agitating and throwing up from the bottom side of said cylinder the material discharged into it from said hopper, substantially as set forth. 110

4. In an air-separator, the combination of an inclined cylinder closed at its upper end and having an air-inlet at its lower end, with an air-outlet at its upper end located at such a distance from the closed end of said cylinder as to form a settling-chamber therein, and a suitable hopper arranged centrally with 125 respect to the length of said cylinder for feeding material thereto.

5. In an air-separator, the combination of an inclined tube closed at its upper end and open at its lower end for the admission of air 130 and discharge of material, a feed-hopper communicating with the tube near its middle, semi-annular flanges within the bottom of the tube, a rotating shaft in said tube having

beater-arms with lateral screens on their extremities which sweep the spaces between the said flanges and an air-exit opening in the upper side of the tube located at suitable distance from its closed upper end to form a settling-chamber therein, substantially as set forth.

6. In an air-separator, in combination, an inclined tube having an air-inlet opening at its lower end, beater-arms rotating within said tube, a feed-hopper on the side thereof,

a box built above said tube at its middle and opening into the same, said box having an upper outlet, and said beater-arms having screens fastened near their outer ends, substantially as described.

In testimony whereof I hereunto affix my signature in the presence of two witnesses.

CHARLES H. LANE.
